LE ROY F. JONES,
DETACHABLE BOW SUPPORT FOR SHOES.
APPLICATION FILED JAN. 5, 1918.

1,273,376.

Patented July 23, 1918.

Inventor

L.F. JONES

By Watson E. Coleman

Attorney

UNITED STATES PATENT OFFICE.

LE ROY F. JONES, OF WAIAKOA, TERRITORY OF HAWAII.

DETACHABLE BOW-SUPPORT FOR SHOES.

1,273,376.

Specification of Letters Patent. Patented July 23, 1918.

Application filed January 5, 1918. Serial No. 210,544.

To all whom it may concern:

Be it known that LE ROY F. JONES, a citizen of the United States, residing at Waia-
5 koa, in the county of Kula, Maui, and Terri-
tory of Hawaii, has invented certain new
and useful Improvements in Detachable
Bow-Supports for Shoes, of which the fol-
lowing is a specification, reference being had
to the accompanying drawings.

10 This invention has for its object the pro-
vision of very simple means for detachably
supporting a bow upon a slipper or low
shoe, the device being so constructed as to
permit the ready detachment or application
15 of the bow, when desired.

In cleaning white shoes or polishing shoes
of other colors, the ribbon of which the bow
is made becomes very often soiled, unless
extreme care be taken to protect the ribbon
20 and the object of my device is to do away
with the necessity of this care by providing
means whereby the bow may be readily de-
tached from the shoe while the shoe is being
cleaned or polished, the device also permit-
25 ting the ready application or removal of
bows of various styles or colors to shoes.

With these and other objects in view, my
invention consists of the several features as
illustrated in the accompanying drawings,
30 wherein:—

Figure 1 is a perspective view of a slipper
provided with my improved bow attaching
device;

Fig. 2 is a sectional view through a shoe
35 and through the attaching plate 10, the bow
being shown in elevation and the parts be-
ing separated;

Fig. 3 is a like view to Fig. 2, but showing
the parts engaged with each other, the bow
40 not being shown.

Fig. 4 is a face view of the plate 10; and

Fig. 5 is a sectional view showing the
stud 14 and its attachment.

Referring to these drawings, it will be
45 seen that my invention includes an attaching
plate or frame designated 10, which is prefer-
ably made of a piece of thin sheet metal
of any suitable character formed with per-
forations 11 at the corners whereby a bow
50 of ribbon may be attached to the plate and
also formed with a pair of key-hole slots 12
disposed in reverse relation to each other,
that is, with the enlarged portions of the

slots toward each other. A bow 13 may be
attached to the plate 10 by stitching through
the eyes or perforations 11. The shoe is
provided at the point where the bow is to be
attached with outwardly projecting studs
14, these studs having heads and preferably
being formed with prongs 15, whereby the
studs may be attached to the leather of the
shoe. These studs are disposed a distance
from each other equal to the distance of the
narrowed portions of the key-hole slots 12
and when it is desired to dispose the bow
and the supporting plate 10 upon the shoe,
the leather of the shoe is bent upon itself or
contracted so as to insert these studs into
the enlarged portions of the key-hole slots
and when the hand is taken away, the
natural resilience of the leather will cause it
to flatten and the studs will be disposed in
the narrowed portions of the slots, thus
holding the bow support 10 securely to the
leather of the shoe. The reverse operation
will, of course, permit the removal of the
plate or support 10.

It will be obvious that this support 10
may be made of any desired material and
that it may be very cheaply made and that
bows of various ornamental character may
be applied to the plate. Furthermore, it will
be obvious that the headed studs 14 may be
applied to the leather of any character of
shoe and may be initially applied thereto or
85 applied after the shoe is made. These studs,
as illustrated in Fig. 2, are entirely con-
cealed by the bow as is the plate 10. This
device permits the shoe to be cleaned with-
out any danger of soiling the bows thereon. 90

It is pointed out, and it will be obvious
from Figs. 2 and 3 that when the shoe is on
the foot the leather of the upper will be
stretched over the instep and will be pre-
vented from contracting so that, under these
95 circumstances, the studs 14 cannot move to-
ward each other and thus the plate or frame
10 cannot become detached from the shoe.

Having described my invention, what I
claim is:—

100 The combination with a shoe, of out-
wardly projecting headed studs disposed
upon the upper of the shoe at the instep
thereof, and a bow support comprising a
slightly curved metallic plate, said plate
105 having key-hole slots adjacent its ends, the

narrow portions of the slots extending away from each other, said studs being adapted to enter the wide portions of the slots when the leather of the upper is flexed and to engage in the narrow portions of the slots when the leather of the upper is transversely stretched.

In testimony whereof I hereunto affix my signature in the presence of two witnesses.

LE ROY F. JONES.
